Attorney

UNITED STATES PATENT OFFICE.

FRANKLIN J. EVANS, OF WEST HAZLETON, PENNSYLVANIA.

POSITIONING-BUTTON.

1,329,234.

Specification of Letters Patent. Patented Jan. 27, 1920.

Application filed July 25, 1919. Serial No. 313,275.

To all whom it may concern:

Be it known that I, FRANKLIN J. EVANS, a citizen of the United States, residing at West Hazleton, in the county of Luzerne 5 and State of Pennsylvania, have invented certain new and useful Improvements in Positioning-Buttons, of which the following is a specification.

The invention has relation to a device for 10 machinists or tool makers and generally known as a "positioning button" and has for its object, to materially reduce the cost of precision boring operations of the kind that are necessary in making jigs and like work. 15 The invention has for its object the provision of a tool or device of the character specified which will insure a position being located with certainty, the tool embodying a button which can be quickly and easily made 20 to run true and then made secure against displacement, whereby the position may be indicated with accuracy.

The drawing illustrates a preferred embodiment of the invention. However, it is 25 to be understood that in adapting the same to meet different conditions, various changes in the form, proportion, and minor details of construction may be resorted to without departing from the nature of the invention, 30 as claimed hereinafter.

In the accompanying drawing,

Figure 1 is a side view of a tool embodying the invention.

Fig. 2 is a view similar to Fig. 1 partly 35 in section.

Fig. 3 is a section on the line 3—3 of Fig. 2 looking to the right, as indicated by the arrow.

Corresponding and like parts are referred 40 to in the following description and indicated in the several views of the drawing by like reference characters.

The tool consists of a shank 1 having a stem 2 which is of less diameter than the 45 shank 1. An intermediate portion of the body of the tool is screw-threaded as indicated at 3 and receives a clamp nut 4, the outer edge of which is milled or knurled to enable a firm grip being obtained thereon 50 when turning the nut either to clamp or to release the button. An axial opening 5 is formed in the stem 2 and is internally threaded to receive a screw 6 upon which is mounted a washer 7 and a button 8. The 55 outer surface or edge of the button 8 is

formed on the segment of a sphere, this being essential to the accuracy of the device when making measurements. The button 8 has its central opening through which the screw 6 passes of larger diameter than the 60 screw, so that the button may be adjusted within certain limits to insure its running true, even though the shank or body of the tool may wobble or run out of true.

A clamp sleeve 9 is mounted upon the 65 stem 2 and has a limited longitudinal movement thereon. A longitudinal slot 10 formed in a side of the clamp sleeve receives a screw 11 which is threaded into the stem 2 and provides means for securing the clamp 70 sleeve in the required adjusted position. The inner end of the clamp sleeve is enlarged, as indicated at 12 so as to present an extended surface for the action of the clamp nut 4. The outer end of the clamp sleeve has an 75 inner flange 13 which forms an abutment for one end of an expandable helical spring 14 which is located within the sleeve and confined between the end of the stem 2 and the flange 13. The spring 14 normally presses 80 the sleeve 9 outwardly, so as to grip the button 8 between the end of the sleeve and the washer 7 in a manner to admit of the button being adjusted and retained in the adjusted position during its securing by turning the clamp nut 4, so as to cause the sleeve 85 to clamp the button between its outer end and the washer 7.

In practice the shank 1 of the device is slipped into the chuck of a milling machine 90 or other machine and is made secure. The device is now rotated and the button 8 is caused to run true by pressing a suitable object against the outer edge thereof, such as a piece of wood. After the button 8 has 95 been caused to run true, the machine is stopped and the button made secure by turning the clamp nut 4 to cause it to come in contact with the inner end of the sleeve 9, and exert a pressure thereon so as to 100 firmly grip the button between the outer end of the clamp sleeve and the washer 7. The button by reason of its outer curved edge constitutes a segment of a sphere, hence close and accurate measurements may be made, 105 as will be readily understood.

The foregoing description and the drawing have reference to what may be considered the preferred, or approved form of my invention. It is to be understood that I may 110

make such changes in construction and arrangement and combination of parts, materials, dimensions, et cetera, as may prove expedient and fall within the scope of the appended claims.

Having thus fully described my invention, what I claim as new and desire to secure by Letters Patent is:—

1. A tool of the character specified, comprising a shank having a stem, a clamp nut on the shank, a button on the shank and movable transversely thereof in every direction, means for temporarily holding the button in a given position and means acting 10 jointly with the clamp nut for securing the button in the required adjusted position.
2. A tool of the character specified, comprising a shank having a stem, a button on the stem and movable transversely thereof, in every direction, a sleeve on the stem, means yieldably pressing the sleeve against the button for temporarily holding the same in a given position and a clamp nut on the shank and adapted to engage the sleeve and 20 move the same to permanently secure the button in the required adjusted position.
3. A device of the character specified, comprising a shank having a stem in which is formed a threaded axial opening, a screw 30 threaded into said axial opening, a button mounted on the screw and movable laterally thereon in every direction, a clamp sleeve on

the stem and having its outer end in engagement with the button and a clamp nut on the shank and coacting with said sleeve to 35 secure the button in the required adjusted position.

4. A tool of the character specified, comprising a shank, a button supported by the shank and movable transversely thereof in 40 every direction, a sleeve on the shank and having its outer end in contact with the button to retain it in position, and a clamp nut mounted on the shank and coacting with the sleeve to fix the position of the button 45 after the same has been adjusted.

5. A tool of the character specified, comprising a shank having a stem, a screw engaging an axial opening of the stem, a button mounted on the screw and movable laterally in every direction, a sleeve mounted on the stem and having an inner flange at its outer end, an expansible helical spring between the end of the stem and the inner flange of the sleeve and a clamp nut mounted 50 on the shank and coacting with the sleeve to secure the button in the adjusted position.

In testimony whereof I affix my signature in presence of two witnesses.

FRANKLIN J. EVANS.
